(57) **CLAIM**

The ornamental design for an electrical power controller, as shown and described.

DESCRIPTION

FIG. 1 is a front elevational view of an electrical power controller showing our new design;

FIG. 2 is a rear elevational view thereof;

FIG. 3 is a top plan view thereof;

FIG. 4 is a bottom plan view thereof;

FIG. 5 is a right-side elevational view thereof;

FIG. 6 is a left-side elevational view thereof;

FIG. 7 is a front, top and right-side perspective view thereof; and,

FIG. 8 is a front, top and right-side perspective view thereof. The broken lines in the drawings illustrate portions of the electrical power controller that form no part of the claimed design.
